[57] CLAIM

The ornamental design for a bike safety light, as shown, and described.

DESCRIPTION

FIG. 1 is a perspective view of a bike safety light showing my new design, with the wires broken away to indicate indeterminate length;

FIG. 2 is a right side view thereof;

The left side is a mirror image of the right side;

FIG. 3 is a front view thereof;

FIG. 4 is a rear view thereof;

FIG. 5 is a bottom view thereof; and,

FIG. 6 is a top view thereof.
